SELECTORS FOR AUTOMATIC PHONOGRAHS

Clarence W. Schultz, Arlington Heights, and George F. Boesen, Park Ridge, Ill., assignors, by mesne assignments, to The Seeburg Corporation, a corporation of Pennsylvania

Application August 30, 1954, Serial No. 452,876

20 Claims. (Cl. 274—10)

This invention relates to selectors for automatic phonographs which are arranged to receive and store a plurality of signals each corresponding to an individual recording.

Heretofore, such selectors have normally included members corresponding individually to a recording, which members are physically displaceable from normal to selected positions and vice versa. When one or more such members are displaced, the machine goes into automatic operation until all the corresponding recordings have been played and all the displaced selecting members have been returned to normal position. Such machines normally include a movable element which is arranged to cooperate with a displaced selecting member in such manner that the corresponding record is supplied to the playing mechanism for the reproduction of the selected recording. The movable selector element is arranged to move through selecting positions corresponding to all the records in the magazine, and in a phonograph arranged to play both sides of each record, means are provided for determining which side of the record is to be played.

In one well known type of machine, the records are stored in a stationary magazine and the player unit is moved along the magazine. When a selection is made displacing a selecting member, the playing unit starts to move past the magazine in one direction and then in the other direction. When an element on the playing unit engages the displaced selecting member, the playing unit is arrested and put into its operating cycle to remove the corresponding record from the magazine to the playing unit for playing and return to the magazine. In one type of machine, the left sides of records are played when the playing unit is conditioned for travel in one direction and the other sides of the records are played when the playing unit is conditioned for travel in the opposite direction.

In accordance with the present invention, we provide magnetizable memory elements, one for each available recording. When a selection is made, the corresponding magnetizable memory element is magnetized in a definite sense or polarity. A complete program may be set up by thus magnetizing any desired number of magnetizable elements. When selections are made so as to magnetize the memory elements corresponding to the recordings desired to be played the motor switch is closed so that the mechanism goes into operation and the movable selector member, for example, the playing unit, starts to move through a plurality of selecting positions. In each selecting position, it cooperates with the magnetizable memory element which is associated with the recording corresponding to said position. Those memory elements which correspond to recordings which have been selected for playing will be magnetized in the definite sense referred to above and when the movable selector member is in a position so as to cooperate

2

with such a selected memory element the movable selector member will be arrested in that position and the recording corresponding to such position will be played.

In the preferred embodiment of the invention herein-after described, the movement of the selector element through a definite selecting position causes the application of a magnetic field to the corresponding magnetizable element and if such element has been selected and thus magnetized in the definite sense above referred to 10 this field tends to reverse the magnetization of the magnetizable element whereas if the corresponding magnetizable element has not been so selected and is thus already in a reversed state of magnetization then no appreciable effect is produced by the application of this field. Thus normally all the magnetizable elements are left 15 in this reversed state of magnetization. When an unselected magnetizable element is thus subjected to this field, no change of flux occurs in the magnetizable member. When, however, a field is applied to a selecting magnetizable member, that is, one which is magnetized in the aforesaid definite sense, there is a reversal of magnetization and a resulting change in the flux of that element.

In the modification of the invention described, a circuit 20 is coupled to a plurality of magnetizable memory elements so that a voltage occurs therein when the magnetization is reversed and this voltage, preferably amplified and extended time wise, is employed to trigger a suitable relay which results in the arresting of the movable selector member and the playing of the corresponding recording. This corresponding recording is that one determined by the position of the movable selecting member, and in the case of the preferred embodiment, by the direction in which that selector member is moving at the time that said voltage is created by a change 25 in the flux of a selected memory element.

The invention will readily be understood from the following description of a preferred embodiment thereof, taken in conjunction with the accompanying drawings, 30 in which:

Figure 1 is an end elevation of a phonograph comprising the improved selector;

Fig. 2 is a diagrammatic view of four corners of a memory element mounting board or matrix;

Fig. 3 is an enlarged fragmentary view of one of the 35 toroids and related conductors of the matrix;

Fig. 4 is a substantially rectangular BH curve of a ferrite material preeminently suitable for the present invention; and

Fig. 5 is a wiring diagram.

Referring to the drawings, Figure 1 shows a phonograph of well known type which is described and claimed in the co-pending application Serial No. 132,147, filed December 9, 1949 by Herman G. Jensen now U.S. Patent 2,716,550. This phonograph comprises a base 10 which supports spacers 11 which provide spaces for a series of vertical records 12. The playing unit 13 is movable on the base 10 to and fro along the magazine by means of a reversible motor (not shown) on the unit. The reversal of the motor is effected by means of a reversing switch 14 which engages an abutment 15 at each 60 end of its travel.

The playing unit includes a trip relay 16 which is arranged to be energized by a selecting impulse and thus 65 effect the playing of a selected recording. When the relay 16 is energized the playing unit will be arrested in a selected position, a transfer arm 17 will be actuated so as to lift the selected record into playing position; a clamping member 18 will be actuated so as to secure the record in said position on the playing unit; and the

player arm 19 will be applied to the record in the initial playing position. After the selected recording has been reproduced, the playing mechanism is tripped to effect the removal of the player arm 19 from the record and its return to initial playing position. The actuation of said mechanism also effects the release of the played record and the return of the transfer arm 17 to its normal position as shown in Figure 1, so that the played record is returned to its space in the magazine. Thereupon the travel of the player unit 13 is resumed until the trip relay 16 receives another selecting impulse. It may be noted that at each end of the travel of the playing unit the player arm is moved to the other side of the playing position to correspond to the reversal of the drive of the motor, so that the left hand side of a record is played when the player unit is arrested when moving in one direction and the right hand side of a record is played when the player unit is arrested when moving in the opposite direction. The mechanism above referred to is fully described in the above identified application.

In accordance with the present invention we provide a magnetizable element, specifically a toroid 20, for each recording in the machine. In other words there is an individual toroid corresponding to each side of each record in the magazine. To select any particular recording the corresponding toroid is magnetized in a definite sense.

The machine described herein is arranged to play fifty records and for convenience the recordings and the toroids are identified as A1, A2, . . . A10, B1, B2, . . . B10, C1, C2, . . . C10, . . . K1, K2, . . . K10 (I is not used to avoid confusion with 1). Selections are made by actuating one of two series of 10 switches each. One series 26 of switches is lettered A, B, C, . . . H, J, K (see Fig. 5). The other series of switches 25 is numbered 1, 2, 3, . . . 8, 9, 10. As will hereinafter more fully appear, actuation of switches A and 1, for example, effects the magnetization of the toroid A1 in the definite sense, thus storing a signal which will result in the playing of the recording A1, and so forth. Such actuation would normally be effected by buttons (not shown) conveniently arranged on the exterior of the machine.

The toroids 20 are mounted in a matrix 27 (shown best in Fig. 2) which may suitably be mounted on the base 10 as shown in Figure 1. A conductor 22, A (Fig. 2), extends horizontally through the toroids 20(A1, A2, . . . A10). A conductor 22, B, extends horizontally through the toroids 20, B1, B2, B3 . . . B10, and so forth. A conductor 23 (No. 1) extends vertically through the toroids 20(A1, B1, C1, . . . K1). A conductor 23 (No. 2) extends vertically through the toroids 20, A2, B2, C2, . . . K2, and so forth. Thus each toroid 20, A1, for example, has a vertical conductor 23 (No. 1) and a horizontal conductor 22, A, extending through it. (When referring to Fig. 5, the wiring diagram, it should be noted that the horizontal conductors 22 are here shown in vertical positions and separate from vertical conductors 23 so as to simplify this figure and for their true position relative to toroids 20 and conductors 23 it is necessary to refer to Fig. 2.) As will hereinafter appear, when selection A1 is made, current passes by these two conductors (22A and 23 No. 1) through the toroid A1 simultaneously and in the same electrical direction so that their magnetizing effect is additive and sufficient to magnetize the toroid A1 in the definite sense mentioned above. At the same time, a lesser current flows through all the toroids A2, A3, A4 . . . A10 and through all the toroids B1, C1, D1, E1, . . . K1 without appreciable magnetizing effect due to the magnitude of the current and the magnetic characteristics of the material of the toroids, as will be more fully explained.

A strip of insulation 24 is mounted on the base 10 along the magazine (Fig. 1). This strip is provided with a series of fifty contacts A1, A3, A5, A7, A9, B1, B3, B5, B7, B9, . . . K1, K3, K5, K7, . . . K9—the odd

ably comprise vertical wires extending between studs 45 on the base 39 as shown in Fig. 2. These studs are relatively large so that the grids are located clear of the other conductors on the base 39. It is to be noted that all the conductors passing through the toroids are insulated from each other. The vertical wires forming the odd numbered grid 35 are connected together at their upper ends and are connected to one side of the switch 37 by a conductor 46 (Figs. 2 and 5). The vertical wires included in the even numbered grid 36 are connected together at their lower ends and by a conductor 47 to the other side of the switch 37. This switch has a grounded common pole so that one or the other of the grids 35 or 36 is grounded, depending upon the direction of travel of the playing unit and the sides of the records which it is conditioned to play. Since the switch 37 is on the reversing switch 14, the switch 37 is actuated from one position to another at the end of the travel of the playing unit.

We prefer to employ condensers to supply the selecting current to the common conductors 23 and 22 and to supply the current to the individual conductors 34 which effect magnetization of the toroids in opposite senses. These condensers are numbered 48 and 49 respectively (Fig. 5). The source of voltage 50 is designed to provide 50 volts. The conductor 33 connects the brush 30 to one side of the condenser 49 and, through a resistor 51, to the movable arm of a high resistance voltage divider 52. One side of the voltage divider 52 is connected to the voltage supply line 50. The other side is grounded as is the other side of the condenser 49. It will readily be understood that when the brush 30 is out of engagement with the contacts 28 and 29, the condenser 49 is charged to a voltage which is determined by the adjustment of the voltage divider 52. When the brush 30 engages a pair of contacts from the series of contacts 28 and 29, the condenser 49 is discharged through one of these contacts and through one of the individual conductors 34 to the toroid associated with that contact and thence to the grid 35 or 36 depending upon which grid is grounded. The setting of the voltage divider is arranged so as to insure complete reverse magnetization of any selected toroid 20. Preferably the brush 30 moves out of engagement with the contacts 28 and 29 when the playing unit is arrested. However, the resistance of resistor 51 is made sufficiently high so that the only time that an appreciable current can flow is when the condenser 49 is being discharged.

The source of voltage 50 is also connected to one side of a high resistance voltage divider 53, the other side of which is grounded. The movable arm of the voltage divider 53 is connected through a resistor 54 to the conductor 43, which is connected to one side of the condenser 48, the other side of which is grounded.

As has been mentioned before, the conductor 43 is connected to the conductors 23 (No. 1 to No. 10) which extend vertically through the toroids 20 and which are individually connected to one side of the switches 25 by the leads 41. The other sides of these switches are connected to a conductor 55. The conductor 42 is connected to the conductors 22 (A, B, C, . . . J, K) which extend horizontally through the toroids 20 and which are individually connected to the switches 26 by the leads 40, the other sides of said switches being connected to a conductor 56.

In the case of a phonograph intended for home use, the conductor 55 may be connected directly to the conductor 56. However, for a commercial phonograph, it is convenient to provide a switch 57 between them. This switch is arranged to be closed by a play control unit 58 shown diagrammatically. It will be understood that this unit may be energized by suitable coins to close the switch 57 in known manner. If this switch 57 is closed, it will readily be understood that if one switch 25 and one switch 26 are closed, for example A and 3, then the

condenser 48 will discharge through vertical conductor 23 (No. 3) horizontal and conductor 22 (A). In such a case the toroid 20 (A3) is the only one through which two currents pass. The current provided by the condenser 48 is regulated so that the toroid 20 (A3) is magnetized in the definite sense, whereas the other toroids through which the number 3 conductor 23 or the A conductor 22 pass, are unaffected.

One end of the common conductor 38 is grounded. The other end is connected to an amplifier 59 which substantially amplifies the small signal generated on the line 38 by a change in flux in a selected toroid. This signal is ordinarily of very short duration. It may suitably be extended time wise by a conventional multi-vibrator section 60 to energize a gas tube 60' in the multi-vibrator section for sufficient time to insure the actuation of the relay 16.

Means are provided to initiate operation of the phonograph motor 61 (shown in Fig. 5). This motor is connected to a power line 62 and also to a switch 63, the other side of which is grounded. The switches 25 have associated therewith a series of switches 125, likewise the switches 26 have associated therewith a series of switches 126. The power line 62 is connected to one side of each of the switches 125. The other side of the switches 125 is connected to a line 155. The conductor 155 is connected by a switch 157 to a conductor 156 which is connected to one side of the switches 126. It will be understood that the switch 157 is mechanically associated with the switch 57. It is arranged to be closed when the unit 58 retains credit. The switch 157 like the switch 57 may be omitted in the case of a home unit. The other side of the switches 126 is connected to the unit 58 for the purpose of canceling credit therefrom, and is also connected to a relay 64. The other side of the relay 64 is grounded. A switch 65 mounted on the base 10 (Figure 1) at one end of the machine is arranged to be closed by an abutment 66 carried by the bracket 31 each time that the player unit reaches that end of its travel. One side of the switch 65 is connected to the power line 62 (Fig. 5). The other side of the switch 65 is connected to a relay 67, the other side of which is grounded. The relays 64 and 67 are arranged in juxtaposition and are arranged to cooperate with teeth on a rotatable disc 68. The armature of the relay 64 has, pivotally mounted thereon in known manner, a detent 69 which projects through a window 70 which limits its movement such that it can rotate the disc 68 a peripheral distance of two teeth in the counter-clockwise direction. The detent 69 is biased to the right as viewed in Fig. 5. When the relay 64 is energized, the detent 69 moves downwardly into cooperative relation with two teeth 71 on the disc 68.

A spring pressed detent 72 cooperates with a set of teeth 73 also on the periphery of the disc 68. The relay 67 is provided with a similar window 74 and a similar detent 75, the arrangement in this case being that the limited movement of the detent 75 is such that it can rotate the disc 68 one tooth space in the clockwise direction. A pin 76 on the disc 68 is arranged to cooperate with the motor switch 63.

The operation is that when a selection is made by actuating selecting buttons (not shown) placed conveniently on the exterior of the machine, the switches 125 and 126 are closed; the relay 64 is energized; and the detent 69 moves the disc 68 the distance of two teeth in the counter-clockwise direction. When the disc 68 is thus rotated the pin 76 closes the switch 63 so that the motor 61 is put into operation and the player unit moves to and fro until it is arrested by the action of a selected toroid 20.

Whether only one selection is made or whether any plurality of selections are made, the operation of the motor and the travel of the playing unit will continue until the relay 67 is energized twice. The first energization rotates the disc 68 one tooth space in the clockwise

direction without, however, opening the switch 63. It requires a second energization of the relay 67 to effect the opening of the switch 63 and terminate the operation of the motor 61. Thus the carriage will make a complete movement in one direction and a complete movement in the opposite direction after the last selection has been made. This insures the playing of all the selected recordings before the machine ceases to operate as a result of the opening of the switch 63.

The magnetic material employed in the toroids 20 may suitably be any of the modern magnetic materials generally referred to as ferrites which have a B-H curve approaching a rectangle. We have used ferrites composed of iron oxide-manganese oxide and magnesium oxide which have a B-H curve of the characteristics shown in Fig. 4. The normal state of magnetization of the toroid is indicated at 77 on this figure. It will readily be seen that if a field of the magnitude 78 is created momentarily, the magnetization of the toroid is unaffected. On the other hand, if a field of the magnitude 79 is created, the toroid will be magnetized in the opposite sense corresponding to the point 80. It will thus be seen that suitable adjustment of the voltage divider 53 may provide a current through a conductor 22 and a conductor 23 without affecting the magnetization of the toroids through which these lines pass with the single exception of the single toroid through which both energized lines pass. That single toroid is changed magnetically from the condition represented by the point 77 to the condition represented by the point 80, the latter point denoting magnetization in the selecting or the definite sense referred to repeatedly above.

The current supplied by the condenser 49 is sufficient to create a field corresponding at least to the point 81. This field changes the magnetization of a selecting toroid from the condition represented by the point 80 on Fig. 4 back to the normal condition represented by the point 77 on this figure.

The magnitude of the current which has to be supplied to the lines 22, 23 and 34 varies with the size and the material of the toroids. We have successfully used toroids type S-1, size F291, manufactured by General Ceramics. The ferrite used is one of iron oxide-magnesium oxide and manganese oxide composition.

The toroids have an outside diameter of .09", inside diameter of .06" and a thickness of .03". We have found that with these toroids, a current of approximately one-half ampere in the wires 22 and 23 effects magnetization in a definite sense of any toroid through which two energized wires pass without affecting the other toroids through which only one energized wire passes.

The general operation of the machine will be very briefly described. Assuming that in the case of a coin machine, credit is established on unit 58 closing the switches 57 and 157, closure of a switch 25 and a switch 26, for example switches 2 and A, respectively, will cause condenser 48 to discharge through line 23, No. 2 and line 22, A. The peak current is such that only the toroid 20, A2 is magnetized into the definite sense referred to above. As many selections as have been paid for can be made in this manner. Each time a selection is thus made, a switch 125 and a switch 126 is closed, canceling one credit of the unit 58 and energizing the relay 64. This relay effects a counter-clockwise rotation of disc 68 and pin 76 so as to close the switch 63 and start the motor 61 so that the playing unit starts to move to and fro, seeking a selected position.

It is to be noted that when the last selection is thus made, the disc 68 is located so that it requires two actuations of the switch 65 and relay 67 to reopen the switch 63 and terminate the operation of the motor. In other words, when the last selection is made, the machine is conditioned so that the playing unit will have to move twice to one end of its travel thus insuring that all the selections made will be played before the motor stops.

As the playing unit moves in one direction, the condenser 49 is repeatedly discharged through the corresponding toroids 20, that is, the odd number toroids or the even number toroids in accordance with the position of the switch 37. Such a current from condenser 49 passing through a normally magnetized toroid has no effect on the magnetization of the toroid and induces no voltage in the conductor 38. When, however, the current from condenser 49 is passed through a selecting toroid 20, this toroid becomes reversely magnetized and the change of flux generates a voltage in the line 38. With the elements referred to above, voltage thus generated may amount to about one-tenth of a volt. This impulse may suitably be amplified by the amplifier 59 to about six volts. The impulse has a very small period, for example, a fraction of a micro-second. The time period may be increased, for example, to one-tenth of a second by means of a multi-vibrator 60 with a voltage of about seventy-five volts. This impulse, having been thus amplified and extended timewise, is utilized to energize the gas tube 60', which may suitably be a 2050 thyratron, the plate current of which is connected to the trip relay 16.

It will thus be seen that when the playing unit moves into a selected position, the trip relay 16 is energized with the result that the corresponding recording is played and then returned to the magazine after which the player unit resumes its travel seeking another selecting signal. The playing unit closes the switch 65 twice which means that it has reached one end of its travel, moved to the other end and then back again to the first end thus insuring that all the selections made, be they even or odd number, are reproduced before the second impulse on the relay 67 opens the switch 63 terminating operation.

Although the invention has been described in connection with the specific details of a preferred embodiment thereof, it must be understood that such details are not intended to be limitative of the invention except in so far as set forth in the accompanying claims.

We claim:

1. A selector for record reproducing machines having a selector member movable through a plurality of selecting positions and means to arrest said member in a selecting position to effect the reproduction of a corresponding record, a plurality of magnetizable elements, each corresponding individually to a record and a selecting position of said selector member, said elements being magnetizable in a plurality of different senses, selecting means arranged to magnetize any of said elements in a definite sense, means associated with the selector member and successive magnetizable elements for subjecting said elements seriatim to a field which reverses the sense of magnetization and the flux in a selected element as the member moves through the corresponding selecting position, and a circuit coupled to a plurality of magnetizable elements and associated with said arresting means for actuating said arresting means when the flux in a selected magnetizable element is reversed by said magnetization reversing means.

2. A selector for record reproducing machines having a selector member movable through a plurality of selecting positions and means to arrest said member in a selecting position to effect the reproduction of a corresponding record, a plurality of magnetizable elements, each corresponding individually to a record and a selecting position of said member, said elements being magnetizable in a plurality of different senses, selecting means arranged to magnetize any desired elements in a definite sense, means associated with the selector member and successive magnetizable elements for subjecting said elements seriatim to a field which reverses the sense of the magnetization of a selected element as the member moves through the corresponding selecting position, a circuit coupled to a plurality of said elements arranged to acquire a voltage when such sense is reversed, and means

operatively associating said circuit with said arresting means to operate the latter.

3. A selector for automatic phonographs having a selector member movable through a plurality of selecting positions and means to arrest said member in a selecting position to effect the playing of a corresponding record, a plurality of magnetizable toroids made of material having a substantially rectangular hysteresis curve characteristics, each corresponding individually to a record and a selecting position of said member, said toroids being magnetizable in a plurality of different senses, selecting means arranged to magnetize any desired toroids in a definite sense, a circuit coupled with each toroid, means for passing current through each circuit as the selector member moves through the selecting position corresponding thereto, said current being arranged to change the flux and thus the sense of magnetization of a selecting toroid, and a second circuit coupled to a plurality of toroids so as to acquire a voltage when such change of flux occurs, said second circuit being operatively associated with said arresting means.

4. A selector for automatic phonographs having a selector member movable through a plurality of selecting positions, and actuatable means associated with said movable member in any selecting position thereof to effect the playing of a corresponding record, a plurality of magnetizable elements, each corresponding individually to a record and a selecting position of said selector member, said elements being magnetizable in a plurality of different senses, selecting means arranged to magnetize any of said elements in a definite sense so as to store corresponding magnetic signals, means associated with the selector member and successive magnetizable elements for subjecting said elements seriatim to a field which reverses the sense of magnetization and flux as the member moves through the corresponding selecting position, and a circuit coupled to a plurality of magnetizable elements and associated with said actuatable means for actuating said actuatable means when the flux in a selected magnetizable element is reversed by said magnetization reversing means.

5. In an automatic phonograph, in combination, a magazine for records, playing means for records, means for transferring individual records from said magazine to said playing means for playing, a selecting member movable through a plurality of selecting positions each corresponding to a recording, means for initiating the operation of the transfer means, a plurality of magnetizable elements each corresponding to an individual recording and position, said elements being magnetizable in a plurality of different senses, means for magnetizing any of said elements in a certain sense, means cooperating with said member and successive elements seriatim during the movement of said member arranged to create a voltage with a selected element magnetized in said definite sense, and means responsive to said voltage for effecting the operation of the initiating means to effect the reproduction of the corresponding recording.

6. In an automatic phonograph, in combination, a matrix comprising a first set of conductors, a second set of conductors in crossing relation thereto, a plurality of toroids made of a material having a substantially rectangular hysteresis characteristic, each mounted individually on two crossing conductors, said toroids being magnetizable in a plurality of different senses, two sets of switches, each set associated with a set of conductors, whereby actuation of a switch of each set causes current to flow through a conductor of each set, said toroids being of material and the current being so limited that the toroid on both conductors is magnetized in a definite sense, and the other toroids through which only one of said energized conductors passes are substantially unaffected, a selector member movable through a plurality of selecting positions, an individual conductor passing through each toroid, means for supplying opposite current to each last mentioned individual conductor as the

member moves through the corresponding position, whereby the magnetization of the selecting toroid is reversed, a conductor common to a plurality of toroids arranged to generate a voltage when the magnetization of a toroid is thus reversed, and means responsive to said voltage for playing the record corresponding to the position of said selector member.

7. In an automatic phonograph, in combination, a selector member movable through a succession of selecting positions, electromagnetic means arranged to be energized to effect the playing of the record corresponding to the selecting position of the selector member, a matrix of toroids each made of a material having a substantially rectangular hysteresis characteristic and corresponding to a record and a selector member position, said toroids being magnetizable in a plurality of different senses, means for magnetizing any number of said toroids in a definite sense to select the corresponding recordings, means associated with the selector member for creating a reverse magnetizing field for each toroid as the selector member passes through the corresponding selector position, a winding coupled to each toroid and arranged to generate a voltage when a toroid is reversely magnetized, and means operatively connecting said winding to the electromagnetic means whereby the corresponding recording is reproduced.

8. In a selector for automatic phonographs, in combination, a matrix including a first set of conductors, a second set of conductors in crossing relation, a plurality of toroids capable of assuming bistable states of magnetic remanence, said toroids being magnetizable in a plurality of different senses, each mounted on a conductor of each set where they cross, an individual conductor extending through each toroid and a common conductor extending through all the toroids, means for supplying current, in the same electrical direction, to any two conductors, one of each set, whereby the common toroid only is magnetized, a selector member movable through a series of selecting positions each corresponding to a toroid and recording, means controlled by the selector member for supplying opposite current to each individual conductor seriatim, whereby a voltage is created in the common conductor as the result of the demagnetization of a selecting toroid, and electromagnetic means controlled by said voltage to initiate the playing of the corresponding recording.

9. An automatic phonograph having a magazine and a player unit, power means for effecting relative movement between said units to bring any record in the magazine and said player unit into cooperative selective relation, means for arresting said relative movement and initiating the playing of the record, a plurality of magnetizable members each corresponding individually to a record and a definite relative position between said units, said members being magnetizable in a plurality of different senses, means for magnetizing said magnetizable members in a definite sense to store individual magnetic selecting signals, means controlled by the relative movement cooperating individually and seriatim with each magnetizable member to produce a voltage with a magnetizable element magnetized in said definite sense, and means associated with a plurality of magnetizable members and responsive to said voltage for actuating said arresting and initiating means.

10. A selector for automatic phonographs comprising in combination with record transfer and playing mechanisms: a selector member movable in either of two directions through a plurality of selecting positions; a series of electrical contacts arranged in pairs, one pair for each record selecting position and one contact for each side of a recording; means for grounding one contact from each pair such that the one grounded depends upon the direction of travel of said selector member; a series of magnetizable memory elements corresponding to said contacts, said elements being adapted to be magnetized

in a plurality of different senses; conductors extending, respectively, from each of said contacts to the corresponding magnetizable element; selecting means including two series of wires, a wire of each series passing through each of said magnetizable elements, and means for applying simultaneous electrical impulses to a wire of one of said series and a wire of the other series, such two energized wires passing through only one of said magnetizable elements, which is thus magnetized in a certain sense to select a record corresponding to said element and the related pair of contacts; a source of voltage; means carried by said movable selector member for closing said last-mentioned pair of contacts and connecting the magnetizable element corresponding to that contact in the pair which is grounded to said source of voltage when said member is moved to a corresponding selecting position, thus changing the sense of magnetization of said element; and means whereby voltage created by a change of flux incident to said change in the sense of magnetization in such magnetizable element is utilized to cause movement of said selector member to be arrested in a selected position to initiate operation of said record transfer and said playing mechanisms so as to play the record corresponding to the closed pair of contacts and in particular that side of the record which corresponds to that contact in the pair which is grounded.

11. A selector for automatic phonographs comprising in combination with record transfer and playing mechanisms; a selector member movable in either of two directions through a plurality of selecting positions; a series of electrical contacts arranged in pairs, one pair for each record selecting position and one contact for each side of a recording; means for grounding one contact from each pair such that the one grounded depends upon the direction of travel of said selector member; a series of magnetic memory toroids corresponding to said contacts, said toroids being made of a material having a substantially rectangular hysteresis curve characteristic and being adapted to be magnetized in a plurality of different senses, said toroids being arranged in a plurality of rows extending in one direction and a plurality of intersecting rows extending in another direction; conductors extending, respectively, from each of said contacts to the corresponding toroid; selecting means including one series of wires corresponding to the rows of toroids extending in said first direction and another series of wires corresponding to the rows extending in said second direction, a wire of each series passing through each of said toroids, and means for applying simultaneous electrical impulses to a wire extending in one direction and a wire extending in the other direction, such two energized wires passing through only one of said toroids which is thus magnetized in a certain sense to select a record corresponding to said toroid and the related pair of contacts; a source of voltage; means carried by said movable selector member for closing said last-mentioned pair of contacts and connecting the toroid corresponding to that contact in the pair which is grounded to said source of voltage when said member is moved to a corresponding selecting position, thus changing the sense of magnetization of said toroid; and means whereby voltage created by a change of flux incident to said change in the sense of magnetization in such toroid is utilized to cause movement of said selector member to be arrested in a selected position to initiate operation of said record transfer and said playing mechanisms so as to play the record corresponding to the closed pair of contacts and in particular that side of the record which corresponds to that contact in the pair which is grounded.

12. A selector for automatic phonographs having a selector member movable through a plurality of selecting positions each corresponding to a recording, a first set of conductors, a second set of conductors in crossing relation thereto, a series of toroids, each made of a material having a substantially rectangular hysteresis

characteristic and corresponding individually to a recording, said toroids being magnetizable in a plurality of different senses, each toroid being mounted on a conductor of each set where they cross, switch actuatable means for supplying current simultaneously and in the same electrical direction to a single conductor of each set whereby the toroid mounted on these two conductors is magnetized in a definite sense, a conductor common to a plurality of toroids, an individual conductor for each toroid, means responsive to said movable selector member as said member moves through the corresponding selecting position for supplying opposite current to each individual conductor seriatim, said current being of such magnitude as to reduce and thus change the sense of the magnetization of a selecting toroid which has been magnetized in said definite sense so as to produce a change of flux in said selecting toroid, means for reproducing a selected recording, and electromagnetic means associated with said common conductor arranged to be actuated by the voltage generated in said common conductor by the change of flux in the selecting toroid for arresting said selector member in a selecting position and initiating the operation of said reproducing means.

13. A selector for automatic phonographs having a selector member movable through a plurality of selecting positions each corresponding to a recording, a first set of conductors, a second set of conductors in crossing relation thereto, a series of toroids capable of assuming bistable states of magnetic remanence, each corresponding individually to a recording, said toroids being magnetizable in a plurality of different senses, each toroid being mounted on a conductor of each set where they cross, switch actuatable means for supplying current simultaneously and in the same electrical direction to a single conductor of each set whereby the toroid mounted on these two conductors is magnetized in a definite sense, a conductor common to a plurality of toroids, an individual conductor for each toroid, means responsive to said movable selector member as said member moves through the corresponding selecting position for supplying opposite current to each individual conductor seriatim, said current being of such magnitude as to destroy the magnetization of the toroid in said definite sense and magnetize the same in a different sense so as to produce a change of flux in said selecting toroid, means for reproducing a selected recording, and electromagnetic means associated with said common conductor arranged to be actuated by the voltage generated in said common conductor by the change of flux in the selecting toroid for arresting said selector member in a selecting position and initiating the operation of said reproducing means.

14. A selector for automatic phonographs having a selector member movable through a plurality of selecting positions each corresponding to a recording, a first set of conductors, a second set of conductors in crossing relation thereto, a series of toroids made of a material having a substantially rectangular hysteresis characteristic, each corresponding individually to a recording, said toroids being magnetizable in a plurality of different senses, each toroid being mounted on a conductor of each set where they cross, switch actuatable means for supplying current simultaneously and in the same electrical direction to a single conductor of each set whereby the toroid mounted on these two conductors is magnetized in a definite sense, a conductor common to a plurality of toroids, an individual conductor for each toroid, means responsive to said movable selector member as said member moves through the corresponding selecting position for supplying opposite current to each individual conductor seriatim, said current being of such magnitude as to demagnetize the selecting toroid which has been magnetized in said definite sense and remagnetize it in the opposite sense so as to produce a change of flux in said selecting toroid, means for

reproducing a selected recording, and electromagnetic means associated with said common conductor arranged to be actuated by the voltage generated in said common conductor by the change of flux in the selecting toroid for arresting said selector member in a selecting position and initiating the operation of said reproducing means.

15. A selector for automatic phonographs having a selector member movable through a plurality of selecting positions each corresponding to a recording, a plurality of magnetizable elements each corresponding individually to a recording, said elements being magnetizable in a plurality of different senses, conductor means associated with each element to magnetize any element in a definite sense to store a selection, a common conductor coupled to a plurality of elements, an individual conductor coupled to each individual element, means responsive to said movable selector member as said member moves through the corresponding selecting position for supplying current to each individual conductor seriatim, said current being of such direction and magnitude as to reduce the magnetization of a selecting element which has been magnetized in said definite sense and thus change the sense in which the same is magnetized so as to produce a change of flux in said selecting element, means for reproducing a selected recording, and electromagnetic means associated with said common conductor arranged to be actuated by the voltage generated in said common conductor by the change of flux in the selecting element for arresting said selector member in a selecting position and initiating the operation of said reproducing means.

16. A selector for automatic phonographs having a selector member movable through a plurality of selecting positions each corresponding to a recording, a plurality of magnetizable elements each corresponding individually to a recording, said elements being magnetizable in a plurality of different senses, conductor means associated with each element to magnetize any element in a definite sense to store a selection, a common conductor coupled to a plurality of elements, an individual conductor coupled to each individual element, means responsive to said movable selector member as said member moves through the corresponding selecting position for supplying current to each individual conductor seriatim, said current being of such direction and magnitude as to destroy the magnetization of a selecting element which has been magnetized in said definite sense and thus change the sense in which the same is magnetized so as to produce a change of flux in said selecting element, means for reproducing a selected recording, and electromagnetic means associated with said common conductor arranged to be actuated by the voltage generated in said common conductor by the change of flux in the selecting element for arresting said selector member in a selecting position and initiating the operation of said reproducing means.

17. A selector for automatic phonographs having a selector member movable through a plurality of selecting positions each corresponding to a recording, a plurality of magnetizable elements each corresponding individually to a recording, said elements being magnetizable in a plurality of different senses, conductor means associated with each element to magnetize any element in a definite sense to store a selection, a common conductor coupled to a plurality of elements, an individual conductor coupled to each individual element, means responsive to said movable selector member as said member moves through the corresponding selecting position for supplying current to each individual conductor seriatim, said current being of such direction and magnitude as to demagnetize a selecting element which has been magnetized in said definite sense and remagnetize it in the opposite sense so as to produce a change of flux in said selecting element, means for reproducing a selected recording, and electromagnetic means associated

with said common conductor arranged to be actuated by the voltage generated in said common conductor by the change of flux in the selecting element for arresting said selector member in a selecting position and initiating the operation of said reproducing means.

18. In an automatic phonograph, in combination, a selector member movable repeatedly in a path through a plurality of selecting positions corresponding respectively to each of the available recordings, means for reproducing a selected recording, means to arrest said member in a selecting position to effect the reproduction of a corresponding recording, a plurality of magnetizable elements each corresponding respectively to an individual recording, said elements being magnetizable in a plurality of different senses, means for magnetizing any of said elements to store magnetic signals thereon, means cooperating with said selector member and a magnetized selecting element when said selector member reaches a selecting position corresponding to such a magnetized element for remagnetizing said magnetized element in a different sense so as to produce a change of flux in said magnetized element and a resultant electrical impulse, means responsive to said impulse for actuating said arresting means and thus causing the reproduction of a selected recording, and means operably associated with said magnetizing means for conditioning said selector member for travel through at least its complete path.

19. In an automatic phonograph, in combination, a selector member movable repeatedly in a path through a plurality of selecting positions corresponding respectively to each of the available recordings, means for reproducing a selected recording, means to arrest said member in a selecting position to effect the reproduction of a corresponding recording, a plurality of magnetizable elements each corresponding respectively to an individual recording, said elements being magnetizable in a plurality of different senses, switch means for magnetizing any selected ones of said magnetizable elements to store corresponding magnetic selecting signals thereon, means cooperating with said selector member and a magnetized selecting element when said selector member reaches a selecting position corresponding to such a magnetized element for remagnetizing said magnetized element in a different sense so as to produce a change of flux in said magnetized element and a resultant electrical impulse, means responsive to said impulse for actuating said arresting means and thus causing the reproduction of a selected recording, a control switch arranged to be closed by said switch means so as to initiate the travel of said selector member, an actuating switch arranged to be closed by the selector member each time it arrives at a certain point in its travel, and stopping means actuated by the actuating switch requiring two actuations to effect the opening of said control switch and thus terminate the travel of said selector member.

20. In an automatic phonograph, in combination, a stationary magazine, a player unit movable in one direction and in the opposite direction along the magazine through a plurality of selecting positions corresponding respectively to each of the available recordings and conditioned to play one side of records while moving in one direction and to play the other side of records while moving in the opposite direction, a plurality of magnetizable elements, each corresponding respectively to a recording, said elements being magnetizable in a plurality of different senses, switch means for magnetizing any selected ones of said magnetizable elements to store corresponding magnetic selecting signals thereon, means cooperating with said player unit and a magnetized selecting element when said player unit reaches a selecting position corresponding to such a magnetized element for remagnetizing said magnetized element in a different sense so as to produce a change of flux in said magnetized element and a resultant electrical impulse, means responsive to said impulse for arresting the travel of

said player unit in said selecting position and initiating the operation of said player unit so as to reproduce the selected recording, a control switch arranged to be closed by the operation of said switch means so as to initiate the travel of said player unit, an actuatable member arranged to be actuated by the player unit each time it arrives at the end of its travel, and stopping means controlled by two actuations of said actuatable member to effect the opening of said control switch and thus terminate the travel of said player unit.
